(57) **CLAIM**

The ornamental design for a front panel and door for an oven, as shown and described.

DESCRIPTION

FIG. 1 is a front isometric view, showing an ornamental design of a front panel and door for an oven.

FIG. 2 is a top view of the front panel and the door shown in FIG. 1.

FIG. 3 is a right side view of the front panel and the door shown in FIG. 1, the left side being a mirror image thereof.

FIG. 4 is a front view of the front panel and the door shown in FIG. 1; and,

FIG. 5 is a bottom view of the front panel and the door shown in FIG. 1.

The broken lines showing elements in the drawings are for illustration purposes only and form no part of the claimed design.
